LINECASTING AND COMPOSING MACHINE

Louis M. Potts, Evanston, Ill., assignor to Teletype Corporation, Chicago, Ill., a corporation of Delaware

Original application January 2, 1932, Serial No. 584,387. Divided and this application April 13, 1934, Serial No. 720,409

19 Claims. (Cl. 199—18)

The present invention relates to linecasting and composing machines, and more particularly to automatic control units therefor.

This application is a division of copending application Serial No. 584,387, filed January 2, 1932.

A particular object of the present invention is to provide an automatic control unit for linecasting and composing machines in which is included apparatus for selectively releasing a plurality of matrices during the process of line composition in response to a single initiating signal.

Another object of the present invention is to provide a signal responsive automatic control unit for keyboard mechanism in which a series of successive operations is automatically started under the control of a single condition and may be continued for an indefinite period or until arrested by a predetermined condition.

For convenience in describing the present invention and in order to avoid prolixity of description, the above mentioned copending application will be referred to hereinafter as the parent application, a linecasting and composing machine such as disclosed in the accompanying drawings and which is representative of manually controllable commercial structures will be referred to as the principal machine, the apparatus relating primarily to the automatic control of the keyboard mechanism of the principal machine will be referred to as the control unit, and the structure which relates more particularly to the present invention will be referred to generally as the em quad.

In the development of commercial linecasting and composing machines certain conventions have been adapted both in operation and in structural detail which predicate and determine to a certain extent the practice that has been followed in the design of automatic control units for adapting such manually operable principal machines to automatic operation. For example, each keylever of the keyboard mechanism, of which there are a plurality, is designed to effect a single matrix-release operation upon its depression. For ordinary copy work this system is preferable since alphabetical characters are infrequently repeated, but in the case of certain tabulation work and even in the case of ordinary line composition for the purpose of filling in partially composed lines with blank space elements, pluralities of similar blank character matrices or quads are used. In tabulation work where columns of figures and/or items are being quoted it is frequently desirable to fill in parts of lines

with small dots following a foregoing vertical column and preceding another column. Stock and other market quotations as composed for newspaper purposes are examples of this type of tabulation work.

In order to facilitate the composition of this class of matter, the present invention affords a repeating actuator which may be started into operation by a single control signal and one that will continue to release certain matrices until arrested by appropriate arresting means. The invention utilizes certain features afforded by a control unit such as the one explained in the referred to parent application, among which may be mentioned a reciprocating operating bail and a constantly rotating operating shaft.

Certain selectable elements are delegated to associate ones of the various characters that are selected, and of these each is associated with a blocking member with which the several may be associated collectively or individually which blocking member operates during selection and movement of said certain elements into selective position to block its return. While the element is maintained in its selective position it is subjected to the influence of a reciprocating bail, the latter being constantly driven by the principal operating members of the control unit. After a predetermined or complementary number of matrices have been released, the matrix receiving mechanism comes into engagement with a normalizing apparatus which restores or permits to be restored the blocking member to its normal condition and permits the selected element to assume its neutral position. Means are provided for varying the predetermined point at which the return or normalizing apparatus may become effective, so that a correspondingly greater or fewer number of matrices may be released in response to the special signal.

Since the release of consecutive similar matrices, as just described, fully occupies the operating capacity of the composing machine, it is provided in accordance with this invention that the operation of the em quad mechanism shall temporarily disengage the record reader mechanism so that the latter may not continue to receive line composing signals. This is accomplished by providing a circuit breaker operable in association with the quadding-out operation, which lies in the principal control circuit described in the parent application as dominating the operating shaft whose function, among others, is to actuate the record reader mechanism.

A better understanding of the present inven-

tion in all of its applications may be had by referring to the accompanying drawings in conjunction with the following description wherein,

Fig. 1 is a fragmentary front elevation showing 5 a portion of a line composing machine having certain parts of the present invention applied thereto.

Fig. 2 is a plan view of the operating unit with 10 certain portions broken away and other portions conventionally omitted for the sake of simplicity and clearness.

Fig. 3 is a transverse sectional view taken approximately on line 3—3 of Fig. 2 through the 15 principal portions of the control unit with parts broken away.

Fig. 4 is a transverse sectional view similar to Fig. 3 illustrating a condition of operation subsequent to that shown in Fig. 3.

Fig. 5 is a fragmentary sectional view taken on 20 the same line as Figs. 3 and 4 but illustrating a condition of operation subsequent to that shown in Fig. 4, and

Fig. 6 is a diagram of the principal control circuit fully described in the parent application referred to above.

In Fig. 1 of the accompanying drawings there is illustrated with an assembling elevator 11 a conventional assembling slide 12 which lies longitudinally in the path of the assembled matrices 30 and the assembling block 14 when the latter is in its composing position and which, as matrices 13 are received within the block 14, is moved leftwardly by the impact of the successively received matrices.

The matrices are selectively released from their several channels in the storage magazine, as explained in the parent application, under the control of a signal responsive selecting device 57 (Fig. 2). The latter apparatus upon the reception of 40 a matrix selecting signal causes the movement of a corresponding selectable element 15 in a rightward direction, as viewed in Figs. 3 to 5, whereupon the latter, engaging a depending lug 16 of a push bar or weight 17, dislodges it from its vertical position slightly, causing it to assume an inclination as illustrated in Fig. 4. When this occurs lip 18 of an intermittently reciprocating ball 19 engages the depending lug 16 and, as illustrated in Fig. 5, thrusts the weight 17 upwardly as 45 permitted by the clearance 21, causing the abutment portion 22 on the top thereof to engage and lift a release reed 23 (Fig. 5) individually associated therewith to effect the actuation of the matrix release mechanism pertaining thereto. In 50 this manner is performed each of the composing operations of a linecasting machine by the automatic control unit described in the parent application.

One of the elements 24, which is specially illustrated in Figs. 3 to 5, differs somewhat from the general class of elements 17 by being provided with an integral lug 25 which extends sidewardly thereof and is not found upon the general class of elements or weights 17 which function to release associated matrices.

With this weight 24 is associated a T-shaped blocking lever 26, Figs. 1 and 6 pivoted at 27 and influenced clockwise by a spring 28. When the weight 24 is in its normal position, as illustrated 70 in Figs. 1 and 3, its lug 25 is disposed beneath one arm 29 of the T-lever 26 with the lowermost surface of the latter appendage contacting the top of lug 25 under the coercion of the spring 28. An opposite arm 31 of T-lever 26 supports an 75 standing bar 32 which is confined to vertical

movement within a guide bracket 33 secured to the framework of the unit. At its uppermost end bar 32 is provided with an inclined surface 34 in close juxtaposition with a cooperating surface of similar inclination which belongs to a horizontally movable bar 35 supported in brackets which are secured to a stationary part of the principal machine.

When the weight 24, Figs. 3 to 5, is selected in response to its particular control signal, its associated selector bar 15 moves rightwardly to the position illustrated in Fig. 4, dislodging weight 24 and permitting T-lever 26 under the influence of spring 28 to rotate clockwise and interpose its arm 29 in front of the sidewardly extending lug 25 as shown. In back of the several weights 17 and 24 extending horizontally across the control unit is an angle rod 36 (not shown in Fig. 2) longitudinally pivoted at 37, and having a depending arm 38, to which is connected a clutch release lever 39 through the medium of a link 41. A spring 42, urging the depending arm 38 rightwardly, tends to maintain the position illustrated in Fig. 3, but upon the selective movement of any of the weights 17 or the weight 24, the rear 25 edge of the latter engages the angle bar 36, acting against spring 42 and moving the several articulated members into the position illustrated in Fig. 4. As a result, clutch release bell crank 43 is retracted from its effective condition, where- 30 at it normally causes the disengagement of a clutch 44, Fig. 2, permitting the reengagement of of the driving and driven portions thereof and the resulting operation of shaft 45.

Among several functions the shaft 45, one that 35 is concerned in connection with the present invention relates to its operation of the constantly reciprocating ball 19, with which it is connected through link 46, lever 47, pivoted at 48, and lever operating cam 49 which engages the roller 51 car- 40 ried by lever 47. The operation of clutch 44, imparting rotation to driven shaft 45 in this manner causes the oscillation of ball 19, which thrusts its lip 18 upwardly, engaging the depending lugs 16 of those weights 17 or 24, which are 45 in selected position as indicated in Fig. 4 driving the latter members upwardly to actuate their associated release mechanisms. Upon the subsequent return movement of ball 19, the weights are permitted to resume the position illustrated 50 in Fig. 4, but because in the case of weight 24 T-lever 26 continues to block the sidewardly extending lug 25, it may not resume its normal 55 position of Fig. 3. This being true, and angle bar 36 continuing in its clutch-release position, driven shaft 45 is free to rotate and to continue to oscillate ball 19, while the reciprocation of weight 24 continues so long as it is blocked by T-lever 26.

Every movement of weight 24 releases a matrix 60 13, and as the several matrices are receiving in the assembling block 14 they engage the left-hand portion of the assembling slide 12 and are interposed between it and the rotating star wheel 47, the construction and operation of which is familiar in the art of line composing machines. 65 Slide 12 is provided with an extensive graduated portion 48, and carries a stop member 49 which may be predeterminedly adjusted along its length by means of a securing screw 51. As the slide 12 moves leftwardly during the progress of 70 line composition, stop 49 comes into engagement with a cooperating member 52 carried by the horizontally supported bar 35 which is capable of limited horizontal movement.

Bar 35, being impelled by the stop member 49 75

of slide 12, also moves leftwardly, as viewed in Fig. 1, bringing its inclined-end surface into engagement with the cooperating surface 34 of the upstanding bar 32, and thereby camming the latter member downwardly. Bar 32, at all times engaging arm 31 of lever 26, now rotates the latter counterclockwise against the influence of spring 28 until its normal position is restored with its arm 29 resuming the position shown in Fig. 1, whereupon the sidewardly extending lug 25 of weight 24, being unobstructed by arm 29, passes beneath it, as better illustrated in Fig. 3, and permits weight bar 24 to be restored to normal position as was its condition before selection. With the restoration of weight bar 24, angle bar 36 is also permitted to return to its rest position in response to the urge of spring 42. This restoration is consummated when during the final cycle of revolution of shaft 45, a cam G5, Fig. 2, carried thereby engages with its apex the follower roller 66 (Figs. 2, 3, and 4) carried by bell crank 43 rocking the latter counterclockwise about its pivot 67 into effective engagement with the clutch 44. This separates the driving and driven elements of the clutch 44 and arrests shaft 45 in opposition to the tendencies of a spring 68. When bell crank lever 43 again assumes the position as shown in Fig. 3, blocking lever 39 is permitted to resume its position behind it, as shown, and at this instant responds to the urge of spring 42, acting through link 41 and arm 38.

Beneath arm 31 of lever 26 are a pair of contacts 53 which, when lever 26 is in its normal or extreme counterclockwise position, are kept closed, as illustrated in Fig. 1, but following the selection of bar 24 when lever 26 is in its extreme clockwise position, are permitted to come apart so as to open the circuit 54.

This circuit (Fig. 6) contains a start magnet 55, which, as described in the parent application, acts upon a clutch-release assembly 59 and clutch 60 (Fig. 1) and effects the release of the shaft 56, which in turn operates the record reader 57. Other switches or circuit breakers 58 and 59 are also contained in this circuit and relate to certain other control mechanisms described in the parent application, the several of which, together with contacts 53, predetermine the energization of magnet 55 upon the proper condition of each of their respective determining mechanisms. Of particular importance in the instant case is the control of magnet 55 by the contacts 53, which relate to the em quadding mechanism just described, and whereby the record reader is arrested during the effective condition of the em quad or quadding-out apparatus.

Operation

Power obtained from a suitable source of the principal machine drives pulley 61, shaft 45, and through gear train 62 is distributed to the associated shaft 56, which operates the record reader 57. Shaft 45 supplies the motor power for reciprocating ball 19, through lever 41 and link 46 for actuating the several weights 17 and 24 in response to their respective signals.

The selection of any of the selectable bars 15 is determined by an individual distribution of the several code bars 63, which are positioned in accordance with the impressions received by the record reader mechanism 57, forming a source of stored signals such as the register strip 64.

As in the case of any other selection, the distribution of the several code bars 63 is an indi-

vidual condition in response to each signal and selects a bar 15 which dislodges the em quad weight member 24, but upon the restoration of its selectable element 15, weight 24 continues in its selected or dislodged position, because of its obstruction by lever 26 and particularly arm 29 thereof, which is presented in front of the sidewardly extending portion 25, Fig. 4.

As long as bar 24 continues in this position, so long also is angle member 36 maintained in its position as illustrated in Fig. 4, and the latter member, through link 41, continues to maintain clutch-release lever 39 in its extreme clockwise position as illustrated. This renders lever 43 ineffective and permits clutch 44 to continue to remain engaged, thereby causing the driven portion of shaft 45 to rotate continuously. Cam 49, being carried by driven portion of shaft 45, imparts a reciprocating motion to lever 47 and link 46, rocking ball 19 continuously and reciprocating weight 24 until a sufficient number of matrices 13 (em quads in the present case) have been received in the assembling block 14.

What constitutes a sufficient number of em quad matrices may be predetermined in accordance with the character of matter composed and depends upon the total number of matrices 13, which includes those previously assembled as well as the supplemental em quad matrices and also the relative position of stop member 49 upon slide 12. Thus, by adjusting stop member 49 longitudinally of slide 12, a greater or lesser number of matrices 13 may be made to determine the point of engagement between stop member 49 and its associated member 52, which is carried by bar 35. It should be noted that the adjustable stop member 49 may be positioned at other points than coincident with the ends of a line, in which case the supplemental matrices will merely fill in em quads or other characters up to a predetermined point as is requisite in tabular composition. It is also noteworthy that by making the stop member 49 operatively displaceable and by providing a plurality of such members that tabular work of a multiple nature may be executed.

When the predetermined number of matrices 13 have been assembled in block 14 and have, through star wheel 47, succeeded in moving slide 12 leftwardly, at the proper interval stop 49 engaging member 52, moves bar 35 leftwardly, camming bar 32 downwardly by virtue of the cam surface 34. This action by bar 32 restores T-lever 26 to its normal position, whereat it no longer blocks the em quad weight 24. With no obstruction in its path, weight 24 precipitates to its normal position, Fig. 3, interposing its sidewardly extending lug 25 beneath the arm 29 of T-lever 26, by reason of which it blocks lever 26 and prevents it from resuming its clockwise position as urged by spring 28. Arm 31, engaging contacts 53, closes the circuit 54, permitting the energization of magnet 55 and restoring motion to the record reader 57 and its operating shaft 56.

In this way, the selection of weight 24 arrests the further operation of record reader 57 under the control of the em quad selecting signal and by another and independent stimulus; namely, the accumulation of a predetermined number of matrices 13 and block 14, causes the restoration of record reader 57 to operative condition.

It is noteworthy that the last described feature may have application to other than the particularly noted selection; also that numerous alterations may be made in this and other details of

the present invention without departing from the spirit or scope thereof. It is therefore intended not to be limited by any of the particular details of the foregoing specification nor to the accompanying drawings, except as set forth in the hereinafter appended claims.

What is claimed is:

1. The combination of a plurality of function performing weights, a corresponding plurality of selectable bars each having individual control of one of said weights for conditioning it for operation, a set of code bars, sensing means responsive to certain conditions in a tape for accordingly arranging said code bars, said selectable bars being individually responsive to each arrangement of said code bars, means for unitary actuation of each of said weights after it has been conditioned by said selectable bars, and means for repeated actuation of certain of said weights after it has been conditioned by said selectable bars.
2. In a linecasting and composing machine, a plurality of matrix releasing elements, a set of levers each individual to one of said releasing elements, an automatic control unit responsive to stored signal conditions for selectively actuating said levers each in accordance with a signal individual to it, and means associated with certain ones of said levers for releasing a plurality of matrices in response to a stored signal condition.
3. The combination of a plurality of function elements, a set of code selectors for individually conditioning said elements, signal responsive means for selectively setting said code selectors, and means operative following the selection of an element for actuating it singly or for actuating it a plurality of times.
4. The combination of a selector mechanism including a set of code bars, an element moved into selective condition upon a certain arrangement of said code bars, and means for maintaining said element in said selective condition for a variable time interval after said arrangement of code bars has been altered.
5. In an automatic control mechanism for operating a plurality of actuating devices such as control board keylevers, a plurality of automatically controlled actuating members, a common actuator for imparting motion to each of said members in response to a selecting signal for conditioning said members, and means effective in response to certain signals for imparting a plurality of actuating movements to certain ones of said members.
6. In a selector mechanism, a plurality of selectable elements, means for selectively conditioning said element individually, a continuously operative common actuator for motivating said elements, and means for prolonging the selective condition of certain of said elements for thereby subjecting them to the repeated effects of said common actuator.
7. In a casting and composing machine, a magazine having a matrix carrying channel, a matrix release mechanism for said channel, a metering device for recording the accumulation of matrices released, form control means to operate said release mechanism, means controlled by the form to initiate plural operations of said release mechanism, and means controlled by the metering device to stop said operation.
8. Apparatus as indicated in claim 7 in which the stopping means includes a member adjustable to stop said action at predetermined points during line composition.
9. Apparatus as indicated in claim 7 and automatic means to suspend the operation of said form controlled means until said plural action is stopped.
10. In a linecasting and composing machine, a plurality of matrix releasing devices, an automatic control unit for initiating the performance of certain ones of said devices, means responsive to a condition of said automatic control unit for repeating the release operations relative to certain matrices, and means responsive to a condition of said line composing machine for arresting the performance of said means.
11. In an automatic selecting device, a plurality of function initiating elements, a mechanism responsive to stored signals for automatically causing to be actuated each of said elements, means for restoring said elements after each actuation, and means for repeating the performance of a function automatically after its corresponding initiating element has been restored.
12. In an automatic selecting device, a plurality of function performing members, a corresponding plurality of initiating elements for selectively conditioning said members, mechanism responsive to stored signals for automatically actuating one of said elements, means for restoring said elements after each actuation, and means for repeating the performance of one of said members after its corresponding initiating element has been restored.
13. In an automatic selecting device, a plurality of function performing members, a corresponding plurality of initiating elements for selectively conditioning said members, mechanism responsive to stored signals for automatically actuating one of said elements, and means for restoring said elements after each actuation by said mechanism while maintaining its associated member in operative condition.
14. The combination in a linecasting and composing machine of a selector mechanism including a set of code bars, a plurality of selectable elements each moved into selective condition upon a particular arrangement of said code bars, and means for maintaining certain ones only of said elements in selective condition for a predetermined period after an arrangement of said code bars has been altered.
15. In an automatic selecting device, a plurality of function-performing elements each capable of assuming an operative condition and an inoperative condition, means for normally maintaining said elements in their inoperative condition, a corresponding plurality of conditioning members each operative to engage and move one of said elements from its inoperative to its operative condition, apparatus for withdrawing said members cyclically, and means associated with certain ones of said elements for maintaining them in their operative condition though its conditioning member has been withdrawn.
16. In an automatic operating unit, a plurality of elements to be individually selected and operated in response to stored signals, an operating shaft including means responsive to each of a plurality of signals for initiating the operation of said shaft and means for arresting the operation of said shaft following the reception of each signal, apparatus driven by said shaft for actuating said elements, and means in response to the selection of certain of said elements for disabling said arresting means.
17. In an automatic operating unit, a single rev-

olution clutch mechanism, means responsive to certain signals for initiating said mechanism for a single revolution of operation, and means responsive to other signals for initiating said mechanism for a plurality of revolutions of operation.

18. In a mechanism for performing a multiplicity of various functions under the automatic control of stored signals, a signal responsive device for selecting and initiating a function to be operated, and means responsive to a local condi-

tion for determining the number of operations to be performed

19. In combination, a signal controlled selecting device, a plural character actuating mechanism, means controlled by said device to determine a character to be actuated by said mechanism, and means associated with said mechanism to determine the number of times a character is to be actuated.

LOUIS M. POTTS. 10
